UNITED STATES PATENT OFFICE.

FLORENCE R. CHRISTOPHER, OF DETROIT, MICHIGAN.

DESIGN FOR A HAND BAG.

Application filed December 2, 1925. Serial No. 15,600. Term of patent 7 years.

To all whom it may concern:

Be it known that I, FLORENCE R. CHRISTOPHER, a citizen of the United States, residing at Detroit, in the county of Wayne and State of Michigan, have invented a new, original, and ornamental Design for Hand Bags, of which the following is a specification, reference being had to the accompanying drawing, forming a part thereof.

In the drawings:

Fig. 1 is a front elevation of a handbag showing my new design, and

Fig. 2 is a perspective view showing the rear and one side thereof.

I claim:

The ornamental design for a hand bag, as shown.

FLORENCE R. CHRISTOPHER.
